UNITED STATES PATENT OFFICE.

ELMER V. WILLIAMS, EDWIN G. WILLIAMS, AND CHARLES L. DICKERSON,
OF CLINTON, ILLINOIS, ASSIGNEES OF ONE-FOURTH TO RICHARD A.
LEMON, OF SAME PLACE.

CALCULATING-MACHINE.

SPECIFICATION forming part of Letters Patent No. 595,009, dated December 7, 1897.

Application filed November 12, 1896. Serial No. 811,395. (No model.)

To all whom it may concern:

Be it known that we, ELMER V. WILLIAMS, EDWIN G. WILLIAMS, and CHARLES L. DICKERSON, citizens of the United States of America, residing at Clinton, in the county of De Witt and State of Illinois, have invented certain new and useful Improvements in Calculating-Machines; and we do hereby declare the following to be a full, clear, and exact description of the invention, such as will enable others skilled in the art to which it appertains to make and use the same, reference being had to the accompanying drawings and to letters of reference marked thereon, which form a part of this specification.

This invention appertains to improvements in calculating-machines of that class which are primarily intended for addition and also adapted to perform other mathematical calculations.

The object of this invention is to provide an improved calculating-machine in which the keys are all depressed to an equal extent, the depression of the keys releasing a shaft through the intervention of a controlling or governing wheel, the intermittent rotation of the said shaft being communicated to the registering mechanism.

Another object of the invention is to simplify the mechanism for operating the digit-wheels and to improve the general construction of the machine with a view of presenting a compact structure and provide for the positive operation of the several parts upon each depression of a finger-key.

With the above ends in view the invention consists of a spring-actuated shaft in gear with the registering mechanism and a controlling-wheel mounted on the shaft and carrying means operated upon by key-levers to release said shaft and then arrest the rotation thereof.

The invention further consists in the special construction of the mechanism which operates the parts carried by the wheel that controls the rotation of the spring-actuated shaft.

The invention further consists in the particular construction of the controlling-wheel and parts adjacent thereto which govern the extent of rotation of the spring-actuated or driven shaft upon the depression of the key-levers.

The invention further consists in the particular construction and several combinations of the different parts hereinafter described, and specifically or generally pointed out in the claims.

In the accompanying drawings, forming part of this specification, Figure 1 is a plan view of a calculating-machine embodying our improvements. Fig. 2 is a front elevation. Fig. 3 is a vertical sectional view on the line 3-3 of Fig. 1. Fig. 4 is a vertical sectional view on the line 4-4 of Fig. 1. Fig. 5 is a horizontal sectional view of a part of the mechanism. Fig. 6 is a vertical sectional view through the controlling-wheel with adjoining parts which operate upon the same. Fig. 7 is a longitudinal sectional view through several of the digit-wheels. Fig. 8 is a horizontal sectional view of the carriage mounted on the driven shaft. Fig. 9 is a vertical sectional view of said carriage. Fig. 10 is a view of a modification that may be employed in place of the pawls that engage the digit-wheels.

Referring to the drawings, the letter A designates a base-board upon which are secured three upright frames A', A², and A³, which support the mechanism of our improved adding or calculating machine, and through these frames passes a horizontal spring actuated or driven shaft B, a part of said shaft being squared or otherwise formed to permit a gear-wheel, hereinafter described, to rotate therewith and have a longitudinal movement thereon. Upon this shaft is mounted a pinion b in mesh with a train of gearing, having a wheel b' connected to a suitable spring B' and provided with the usual ratchet and pawl. Between the frames A' and A² the shaft B has also mounted thereon a controlling-wheel C, the method of securing said wheel to the shaft being by a set-screw or other equivalent means. This controlling-wheel is in itself a novel feature of our invention and presents ten projecting points or members c, each carrying a stop-pin c', adapted to slide in a transverse aperture therein, and these pins are arranged in a circle concentric with the shaft upon which the wheel is mounted. The stop-pins are provided on one end with a head, and the controlling-wheel carries springs c, the free ends of which are adapted

to frictionally engage the stop-pins. If desired, the stop-pins may be provided with grooves to receive the ends of the springs, which will prevent said stop-pins from being shot out of the apertures in which they are seated, the grooves being of sufficient width not to interfere with the movement of the pins.

Upon the base-board A is mounted a stand-
ard which carries a bell-crank lever D, and
said lever has its upwardly-projecting member cut away or shouldered to terminate in an anvil or hammer d. Adjoining this bell-
crank lever is a stop-block D'. The bell-
crank lever and controlling-wheel operate in
unison, as when one of the stop-pins is pushed
inward the projecting end thereof will abut
against the stop-block, and thus limit the ro-
tation of the spring-driven shaft, and when
the horizontal member of the bell-crank lever
is depressed the shoulder thereof will pass
between the projecting arms or members of
the controlling-wheel, a further depression
causing the hammer or anvil end d to strike
against the projected pin of the controlling-
wheel and push the same out of engagement
with the stop-block. When the bell-crank
lever is released, the upper member thereof
will be moved out of the path of the control-
ling-wheel and said controlling-wheel will
turn, being actuated by the shaft until it is
stopped by the stop-pin that has been pro-
jected by the operation of a key-lever, as
hereinafter described. This controlling-
wheel, in connection with the bell-crank lever,
may be applied to many styles of registering
mechanisms and forms, *per se*, a distinct fea-
ture and complete invention.

E designates the key-levers, a series of
nine levers being pivoted on a cross-bar
mounted between the frames A' and A², and
these key-levers pass through a slotted face-
plate and terminate so that the keys will be
arranged in two banks, preferably four in
the upper and five in the lower, as shown.
The key-levers are provided with springs e³
for holding their forward ends normally
raised. The key-levers are connected by
rods e to a series of levers E', which are jour-
naled on a transverse shaft or support e' in
the upper part of the frame A², and these
levers extend toward the frame A', crossing
considerably above the key-levers and at
right angles therewith, the free ends enter-
ing vertical slots in a plate E², carried by the
frame A'. Each lever E' has formed integral
therewith a depending member E³, said mem-
bers being of different lengths and curva-
tures, so that when actuated they will con-
tact with the headed ends of the stop-pins.
It will be noted at this point that there are
nine keys for operating nine levers, each
lever having a depending member which is
adapted to contact with the stop-pins, the
ends of said depending members being in the
path of but nine of the ten stop-pins, as one
of said stop-pins is supposed to be in engage-

ment with the stop-block. It will also be
noted that each of the nine keys has an equal
amount of depression, each being supported
in the same manner, performing the same
work, and therefore having an equal touch.

Beneath the key-levers E is a frame F,
preferably journaled on the same shaft with
the key-levers, and said frame is provided
with a transverse portion with which the key-
levers engage. From the center of the trans-
verse portion of the frame F projects a mem-
ber f, the end of which engages a slot in the
horizontal member of the bell-crank lever D,
hereinbefore referred to. The frame F is
held normally raised by a spring-actuated
plunger F', which enters a suitable socket,
as F², mounted on the base-board A and con-
taining a helical spring. When any one of
the key-levers is depressed, the frame F is
moved downward and operates the bell-crank
lever to move the vertical member thereof
toward the controlling-wheel.

The features of our invention that have
been so far described may be applied to any
calculating or registering machine to which
it may be adapted, irrespective of the con-
struction of the digit-wheels or equivalent
mechanism.

The shaft B, which is connected by a train
of gearing embodying gears b b' with the
spring B', carries between the frames A² and
A³ a carriage G, consisting of a gear-wheel
G', having ten teeth and an elongated hub g,
upon which is mounted a frame H, having a
forwardly-projecting arm h and upwardly-
projecting member H', and between the side
members of the frame H is mounted a dog I,
having a pawl i, which is spring-actuated in
one direction, the dog and pawl being adapted
to engage a rack-bar J, supported between the
frames A² and A³. The dog is connected, by
means of a link i', to a bar K, which bar is
pivoted at one end to the lower portion of the
frame A³ and engages with a cipher or zero
key pivoted adjoining the frame A², the for-
ward portion of said key passing through a
slot in the frame. By depressing the cipher
or zero key the dog will be released from the
rack-bar J, so the carriage can move a dis-
tance of one notch to permit the gear-wheel
thereon to engage the next digit-wheel, and
in its movement the upwardly-projecting
member H' of the carriage elevates the lock-
ing-pawl that is in engagement with said
digit-wheel. The carriage is automatic in its
action and is drawn toward the end of the
machine having the key-levers by means of
a flexible connection which passes around a
spring-actuated drum S, over a guide-pulley
s, and is attached to the dog I, as shown. The
lever h is for moving the carriage toward the
frame A³. The cipher or zero key is operated
when it is desired to move the carriage from
one digit-wheel to another in adding different
columns.

The digit-wheels are loosely mounted on a
shaft L, said shaft being provided with a se-

ries of stub-pins l , and the digit-wheels have cavities with projecting lugs l' . Between each two adjacent number-faces the peripheries of the digit-wheels are provided with grooves or recesses, with which the gear-wheel G' may mesh, and on one side the digit-wheels have attached thereto gear-wheels L' and on the other side there are projections having peripheral notches l'' , which are centrally extended to abut against the gear-wheel of the adjacent digit-wheel. The shaft L has mounted thereon a sleeve m , having slots m' adjacent to one side, through which passes a pin n , and the shaft L is adapted to have a longitudinal movement in its end bearings, which is limited by the length of the slot in the sleeve. The sleeve is encircled by a spring which bears upon a washer and the end of the frame, the tendency of said spring being to throw the shaft L to one side, so that the pins l thereon will be out of line with the lugs l' on the digit-wheels, and when it is desired to set the digit-wheels to zero the knob on the shaft is drawn so as to compress the spring and move the pins l in the path of the lugs l' , and then by first raising the locking-pawls the shaft can be turned so as to bring the corresponding numbers on the face of the digit-wheels in line. This mechanism provides a simple and effective means for adjusting the digit-wheels. Prior to setting the digit-wheels to zero the carriage is moved beyond the first digit-wheel.

P designates a shaft which carries a series of gear-wheels one less in number than the number of digit-wheels. These gear-wheels P' are adapted to mesh with the gear-wheels L' on one side of the digit-wheels and have projecting fingers p , which are adapted to engage the recesses l'' of the digit-wheels to effect the carrying. The wheels also have on their hubs pins p' , which are adapted to raise locking-pawls R when said pins come in contact with the depending members of said locking-pawls. The locking-pawls R are mounted on a shaft R' , each pawl being attached to a sleeve, which is slotted for the passage of pins r , which engage with the shaft, and to these pins are attached springs, which pass around the sleeves and exert a pressure to force the pawls downward. The shaft to which the pawls are attached has an arm R^2 , the lower end thereof being connected to a helical spring, which is attached to the frame A^2 . The arm being attached directly to the shaft tends to throw the same in such position that the pins will be out of the rear ends of the slots in the sleeves, thus permitting the pawls to rise independently of the shaft, and when it is desired to raise the pawls in unison it is only necessary to turn the knob at the end of the shaft, when they can be elevated, this being desirable in setting the digit-wheels to zero. When the shaft carrying the pawls is turned, it can be moved to one side, so that the specially-constructed ends of the pawls may ride upon the digit-

wheels, and these pawls are independently movable, so that they can be raised by the member H' of the carriage, as well as by the pins or projections p' of the gear-wheels, which are mounted on the shaft P . The ends of the pawls which lie over the digit-wheels are bent to provide portions which will engage with the recesses of the digit-wheels, and are also so constructed as to ride upon the face of the digit-wheels when the shaft is turned and drawn to one side. In setting the digit-wheels to zero the pressure of the ends of the pawls upon the face thereof gives the desired amount of friction, which prevents the digit-wheels spinning on the shaft when said shaft is turned.

Instead of employing pawls, as shown, we may use in lieu thereof the modification shown in Fig. 10 of the drawings, which consists of a disk having a part of its periphery cut away, said disks being mounted on the shaft P and laterally movable thereon. When the notch in the disk comes opposite the face of the digit-wheel, said digit-wheel may move one space or number. This modification is designed for use in carrying and will be thrown in and out of gear automatically as the carriage is moved.

In operation the driving spring B' is wound, the digit-wheels set to zero by turning the shaft which raises the pawls and pulling said shaft to one side, so that the blocks on the ends of the pawl will rest upon the face of the digit-wheels, the knob on the shaft of the digit-wheels is then drawn outward, and by turning the same the digit-wheels are set to zero. The shaft is then released, the corresponding numbers on the digit-wheels being on a line, and the shaft carrying the pawls is allowed to resume its normal position, so that the bent ends of the pawls will rest in the recesses in said digit-wheels. The carriage which has been previously moved to the end of the frame is moved one step or point forward by depressing the cipher-key. This movement lifts the first pawl out of engagement with the groove in the first digit-wheel. The machine is then set for adding. In the meantime the driven shaft has been held against rotation by one of the pins of the controlling-wheel abutting against the stop-block. Now when it is desired to add it is only necessary to depress the desired key, and the key-lever thereof simultaneously moves the bell-crank lever to project the stop-pin of the controlling-wheel which abuts against the stop-block, a portion of said bell-crank lever passing between the members of said controlling-wheel a pin of the controlling-wheel is also pushed inward, and when said movement has been fully completed and the finger-key released the upper member of the bell-crank lever is thrown out of the path of the member of the controlling-wheel, and the shaft is then permitted to turn sufficient to carry the digit-wheel to a point corresponding with the number of the key-lever which

has been depressed. This releasing of the driven shaft B causes a corresponding rotation of the gear-wheel connected to the carriage which turns the digit-wheel, the locking-pawl being held raised by the arm H' of the carriage. When the gear-wheel of the driven shaft turns the digit-wheel, the gear-wheel on the shaft P is also turned, and when it is necessary to carry the pawl is elevated by the projection on the hub of said gear-wheel and the projection or finger on the opposite side meshes with one of the recesses J^2 in the adjacent digit-wheel and turns the same one point. After the first column of figures has been added by depressing the cipher-key the carriage will be moved so that the gear-wheel thereof will mesh with the next digit-wheel, this movement lifting the second pawl and allowing the first to fall into position in engagement with the first digit-wheel.

In performing other calculations than addition—for instance, subtraction—the keys may have an additional set of numbers in reverse order from the main numbers, and the digit-wheels also have a similar supplemental set of numbers to correspond with the numbers on the keys.

The carriage mounted on the driven shaft is so constructed that its operating-lever is of such weight that it will overbalance the projecting arm H', which engages the pawls, and said lever is adapted to rest upon a bar J^2 , one end of which has a notch J^3 to engage said lever h and hold it close to the frame A³ when it is desired to set the digit-wheels, as hereinbefore described. When the lever is out of engagement with the notch, the dog and pawl will engage the rack-bar J.

We do not wish to limit ourselves to the special construction of the parts as herein shown and described, but reserve the right to modify or change the shape and configuration of the parts or substitute mechanical equivalents therefor so long as each part performs the same function.

We claim—

1. In a calculating-machine, the combination of a shaft, a controlling-wheel mounted thereon, a gear-wheel held in sliding engagement with said shaft, digit-wheels mounted so as to be engaged by said gear-wheel; together with keys which when depressed will actuate mechanism to release the controlling-wheel and permit a rotation of the shaft and digit-wheel engaged by the gear-wheel thereon, substantially as shown and for the purpose set forth.

2. In a calculating-machine, the combination of a shaft, a spring for turning the same, a controlling-wheel mounted on the shaft and provided with laterally-movable pins, a gear-wheel longitudinally movable on the shaft, digit-wheels with which the gear-wheel engages; together with keys and mechanism for engagement with the controlling-wheel and pins thereof, for the purpose set forth.

3. In a calculating-machine, the combination with a shaft, of a controlling-wheel mounted thereon, a gear-wheel meshing with registering mechanism, said gear-wheel being movable longitudinally on the shaft which carries the controlling-wheel, pins carried by the controlling-wheel so as to be movable beyond the faces thereof, releasing and stop mechanism engaged by said pins and actuated by key-levers, substantially as shown and for the purpose set forth.

4. In a calculating-machine, the combination with a series of key-levers, of a corresponding series of levers pivoted at right angles thereto and having depending members, a bell-crank lever having an anvil and a projecting portion, a shaft connected with means for rotating the same when released by the depression of the key-lever, a controlling-wheel mounted on said shaft and provided with laterally-movable pins which are projected in one direction by being engaged by the depending members of one of the sets of levers, and in an opposite direction by the anvil of the bell-crank lever, and a gear-wheel laterally movable on the shaft carrying the controlling-wheel for engagement with rotary digit-wheels for the purpose set forth.

5. In a calculating-machine, a plurality of keys, a shaft having mounted thereon a controlling-wheel laterally-movable pins carried by said controlling-wheel, means for changing the position of the pins by the depression of one of the keys, said key operating a bell-crank lever to move one of the keys laterally and release the controlling-wheel and another pin in an opposite direction to effect a stoppage of said controlling-wheel and shaft for the purpose set forth.

6. The combination in a calculating-machine, of a series of key-levers each having a corresponding touch and limit of movement, said key-levers when depressed actuating pivoted levers; of a shaft having mounted thereon a controlling-wheel, laterally-movable pins carried by the controlling-wheel, means for moving one of the keys in one direction by the depression of a key-lever and another in an opposite direction simultaneously, the upward movement of the key moving one of the levers out of the path of the controlling-wheel to permit the partial rotation of the same, and a gear-wheel mounted on the power-driven shaft so as to rotate therewith and actuate the registering mechanism.

7. In a calculating-machine, the combination, of a shaft, a controlling-wheel rigidly secured thereto and provided with pins, key-levers and intervening mechanism for actuating the pins, a stop-block positioned in the path of the pins when projected, a lever for moving the pin out of the path of the stop-block and holding the controlling-wheel against rotation; together with the key-levers and registering mechanism actuated by the rotation of the shaft, substantially as shown and for the purpose set forth.

8. In a calculating-machine, the combination of the shaft, a controlling-wheel mounted thereon and provided with a series of stop-pins, said controlling-wheel having a peripheral groove and springs which contact with the stop-pins, for the purpose set forth.

9. In a calculating-machine having a series of nine keys and levers actuated by the depression of said keys, a controlling-wheel having ten projecting arms and ten stop-pins, a shaft upon which said controlling-wheel is mounted, a gear-wheel also mounted on the shaft having ten teeth, a series of digit-wheels having peripheral recesses corresponding in number to the number of teeth on the gear-wheel mounted on the rotary shaft, a lever, means for moving the same in the path of the controlling-wheel by a depression of the keys to project one of the stop-pins carried thereby and lock said controlling-wheel, said lever being spring-actuated in an opposite direction to release said controlling-wheel, substantially as shown.

10. In combination with the key and registering mechanisms, of a shaft having a controlling-wheel mounted thereon, said controlling-wheel having projecting points and stop-pins, a stop-block mounted adjacent to one side of the controlling-wheel, and a lever D spring-actuated in one direction and moved against the action of its spring by the depression of one of the keys, said lever when depressed locking the controlling-wheel and retracting one of the previously-projected pins so that the power-driven shaft will be permitted to turn when the key is released.

11. In a calculating-machine, the combination with the key-levers, of a spring-supported

frame having a projecting member, a bell-crank lever, one of the members thereof being engaged by the projecting member of the frame, the key-levers being positioned above a cross-bar of the frame, levers connected to the key-levers and provided with depending members, a controlling-wheel mounted on a shaft, a series of pins carried by the controlling-wheel with which the depending members of the levers engage when the key-levers are depressed, the depression of the key-levers also actuating the bell-crank lever to move the same in the path of the controlling-wheel, the controlling-wheel being released by the upward movement of the key-levers to permit a rotation of the power-driven shaft; together with registering mechanism actuated by said power-driven shaft.

12. The combination with a series of digit-wheels mounted on a shaft, means for adjusting said digit-wheels thereon, of a series of pawls having laterally-extended portions for engagement with recesses in the digit-wheels and enlarged ends adapted to ride on the faces of the digit-wheels, the shaft upon which the pawls are mounted having means for elevating said pawls in unison and moving the same laterally to effect the disengagement of the laterally-bent ends of said pawls from the grooves in the digit-wheels.

In testimony whereof we affix our signatures in presence of two witnesses.
